UNITED STATES PATENT OFFICE

JOSEPH H. LONG, OF CLEVELAND, OHIO

RADIATOR FOR HOT WATER OR STEAM

Application filed May 24, 1932. Serial No. 613,281.

This invention relates to heating devices and more particularly to a radiator to be placed in a building or the like.

An object of this invention is to provide a radiator which can be heated through either steam, hot water or any other desired heating means which can be mounted in any desired position within a room so as to heat the air within the room.

10 Another object of this invention is to provide a radiator of exceedingly simple construction which is capable of being manufactured out of relatively light weight material so that it will not be unduly heavy as are the radiators at present in use.

The above and various other objects and advantages of this invention will in part be described and in part be understood from the following detailed description of the 20 present preferred embodiment, the same being illustrated in the accompanying drawing, wherein:

Figure 1 is a longitudinal vertical section taken substantially on the line 1—1 of 25 Figure 2.

Figure 2 is a transverse sectional view taken on the line 2—2 of Figure 1.

Figure 3 is a fragmentary top plan view of the device.

30 Referring to the drawing wherein like numerals of reference designate corresponding parts throughout the several views, the numeral 10 designates generally a housing or outer jacket which is supported by means of leg members 13 or the like. A heating coil or member 11 is mounted in the lower

35 portion of the housing or jacket 10 and is preferably disposed in a horizontal position and may be connected by means of a pipe 12 to a suitable source of heating supply such as a boiler or the like. The opposite end of the coil 11 is connected by means of a pipe 14 to the heating means so as to effect circulation through the coil 11.

40 The jacket or housing 10 is provided with a bottom wall 15 which terminates rearwardly of the front wall 16 of the housing providing an air intake opening 17 whereby the unheated air is admitted to the lower

50 portion of the housing and is permitted to

circulate about the heater 11 and pass upwardly through the interior of the housing 10 and out through the top of the housing 10.

55 Preferably the housing 10 is provided with a top 18 which has a plurality of outlet openings 19 to permit the heated air to pass outwardly of the housing 10 and into the atmosphere. The hot air which is disposed within the housing 10 will heat the walls of the housing and in order to provide 60 means whereby this heated air will in turn heat additional air, I have provided a manifold or box 20 which is open, as at 21, at the forward or front side and which is supported by means of rods 22 in a position 65 above the heating member 11.

The front wall 16 is provided with an elongated opening registering with the opening 21 of the manifold 20 so that unheated air may freely pass into the interior of this manifold 20. A plurality of vertically disposed heating pipes 23 are secured at one end to the top of the manifold 20 and extend vertically within the housing 10 and are connected at the upper end to the top wall 18. 70 These heating pipes are open at each end and extend through the top wall 18 so that as the air enters the lower portion of the heating pipes 23 and rises under the heating thereof, it will be permitted to freely pass out through the upper ends thereof. It will be noted from the foregoing that the hot air rising within the jacket or housing 10 will circulate about the heating pipes 23 and heat 75 these pipes which in turn will heat the air 80 within the pipes.

85 In the use and operation of this device, the coil 11 may be heated through the medium of a suitable heating means such as hot water or steam, gas or the like, and the heat 90 radiated from this coil 11 will be communicated to the lower boxing or manifold 20 so as to heat this manifold and cause the air to rise upwardly in the heating tubes 23. As the air within the jacket 10 is heated, 95 it will rise in this jacket and circulate about the heating pipes 23 and pass outwardly of the openings 19 into the atmosphere or interior of the room. So long as the coil 11 100 is heated, the air can pass freely through

the intake opening 17 and through the opening 21 of the manifold 20.

It will be obvious that the jacket and heating means including the manifold 20 and the pipes 23 can be constructed of any desired material and made of relatively light sheet metal which will readily radiate heat, thereby greatly reducing the cost of manufacture of the radiator and permitting its use at 10 a point where a relatively heavy radiator is undesirable.

It is, of course, understood that various changes and modifications may be made in the details of construction and design of 15 the above specifically described embodiment of this invention without departing from the spirit thereof, such changes and modifications being restricted only by the scope of the following claims.

20 What is claimed is:—

1. A radiator comprising an outer jacket, having an intake opening in the lower portion thereof and an outlet opening in the upper portion thereof, a heating element 25 within the jacket, a manifold disposed in the jacket above the element and opening through one wall of the jacket, and a plurality of tubes connected at one end to the manifold and connected at the opposite end 30 to the top wall of the jacket, said opposite end being open to the atmosphere.

2. A radiator comprising a jacket having an intake opening in the lower portion thereof, a horizontally disposed manifold disposed in the jacket above the intake opening having a length substantially equal 35 to the length of the radiator and a depth less than the depth of the jacket and opening through one vertical wall of the radiator, and a plurality of heater tubes connected 40 at one end to the manifold and at the opposite end connected to and extending through the top wall of the jacket.

3. A radiator comprising an outer jacket 45 having an intake opening in the bottom wall thereof and outlet openings in the top wall thereof, a heating element disposed longitudinally of the radiator adjacent the bottom thereof, a manifold having a length substantially equal to the length of the jacket and positioned at a point spaced upwardly 50 from the heating element, said manifold opening through one wall of the jacket whereby to permit the air to freely enter the manifold, and a plurality of heater tubes 55 each connected at one end to the top of the manifold and at the opposite end connected to and extending through the top wall of the jacket.

60 4. A radiator comprising an outer jacket having an intake opening extending longitudinally of the bottom wall and adjacent one side, a horizontally disposed heating element positioned at a point spaced upwardly 65 from the bottom wall, means for

connecting the heating element to a source of heating supply, a manifold, means for mounting the manifold at a point spaced upwardly from the heating element, said manifold having one wall thereof open to the 70 atmosphere through a confronting wall of the outer jacket, said outer jacket having a plurality of outlet openings in the top wall thereof, and a plurality of tubes open at each end and each connected at one end to the 75 top of the manifold and at the other end connected to and extending through the top wall of the outer jacket.

In testimony whereof I hereunto affix my 80 signature.

JOSEPH H. LONG.
